UNITED STATES PATENT OFFICE

101,598

DESIGN FOR A COMBINED HOPPER, POWER UNIT, AND FAN CASING FOR STOKERS

Hurshel H. Fitch, Auburn, Ind., assignor to Auburn Foundry, Inc., Auburn, Ind., a corporation

Application July 17, 1936, Serial No. 63,901

Term of patent 7 years

To all whom it may concern:

Be it known that I, Hurshel H. Fitch, a citizen of the United States, residing at Auburn, in the county of De Kalb and State of Indiana, have invented a new, original, and ornamental Design for Combined Hopper, Power Unit, and Fan Casing for Stokers, of which the following is a specification, reference being had to the accompanying drawing, forming part thereof.

The figure is a perspective view of the combined hopper, power unit, and fan casing for stokers, the opposite side being substantially plain and showing my new design.

I claim:

The ornamental design for a combined hopper, power unit, and fan casing for stokers, as shown and described.
